Application November 29, 1943, Serial No. 512,144

12 Claims. (Cl. 178—34)

1

This invention relates to electrically actuated printers suitable for use with electrical control apparatus of the type which selectively energizes actuating elements of the printer, such as magnets, which control the character selecting and printing mechanism. The invention is applicable to printers provided with a type wheel on which the characters are arranged in a plurality of circumferential rows, being selected by a combination of rotary and axial movements of the type wheel.

An important purpose of the invention is to provide improved character-selecting mechanism. A feature of this mechanism is a novel arrangement for selectively rotating the type wheel. Another feature involves the use of a type wheel having at least three circumferential rows of characters, the wheel being located with an intermediate row in printing position when at rest between actuating impulses, requiring only a short axial shift of the wheel to bring either end row into position for printing. A further feature is the use of a short row of characters with an intermediate character in printing position when the type wheel is at rest, requiring a minimum of rotary selective movement to bring any character into position. The combination of these features provides a minimum of combined selective movement of the type wheel, resulting in increased speed of operation, especially when the apparatus includes means for simultaneous rotation and axial shift of the type wheel, as disclosed herein.

Other features include an improved construction and arrangement of tape and ribbon feeding apparatus, adapted to provide not only efficient operation but also a compact and convenient construction adapted for mounting in a case with the printed tape in suitable position for convenient reading, and an improved construction and arrangement of actuating magnets and connecting mechanism. Other objects and advantages will appear from the following description considered in connection with the accompanying drawings, in which

Fig. 1 is a face view of the left side of a telegraph printer;

Fig. 2 is a rear view thereof partly in section taken along the line 2—2 at the left of Fig. 1;

Fig. 3 is a front view thereof partly in section taken along the line 3—3 at the right of Fig. 1;

Fig. 4 is a front view of ribbon feeding mechanism;

Fig. 5 is a section on line 5—5 of Fig. 4;

Fig. 6 is a schematic view of the type wheel actuating mechanism;

Fig. 7 is a face view similar to Fig. 1 showing a modified form;

Fig. 8 is a face view of said form taken from the lower side of Fig. 7;

Fig. 9 is an end view taken from the left of Fig. 7;

Fig. 10 is a detail on line 10—10 of Fig. 8 showing part of the actuating mechanism; and

Fig. 11 is a detail view showing the tape feeding roll drive.

In accordance with a novel feature of the present invention, an aggregate motion mechanism is provided for selectively rotating the type wheel, including a number of levers which are successively connected together in cascade by means of flexible bands or belts rather than by means of the usual connecting rods or pins and sliding links. The ends of the levers to which such bands or belts are joined are formed as arcs of circles about the fulcra of the respective levers and the belts lie against these arcuate portions in such manner that rocking of a lever merely shifts the corresponding belt longitudinally but does not cause a tilt of the direction of such belt. By such an arrangement the multiplication factors of the several levers of this system remain constant regardless of movement of the other levers. Thus the aggregation of motion performed by this mechanism is linear at all times, so that the motional output of such mechanism can readily be arranged to correspond to a number of uniformly spaced positions of a type wheel positioning member.

The combination of levers with flexible bands furthermore results in unusually low friction and small inertia and renders the action of the linkage more perfectly reproducible than if connecting rods and pivots or pins and slots were employed.

Referring more particularly to Figs. 1, 2 and 3 of the drawings, the principal frame-work of the machine comprises a vertical plate P31, from the front end of which two integral ears P32 and P33 project toward the left of Fig. 3 and near the rear of which is attached a plate P34 which also extends toward the left parallel to said ears. A vertical plate P35 is supported from ears P32 and P33 on the front and from plate P34 on the rear. Within the box-like space thus formed by plate P31, plate P35, plate P34 and ears P32 and P33 are mounted six selecting magnets, CM1, CM2, CM3, CM4 and CM5, and a print magnet PM provided with corresponding armatures P36A, P36B, P36C, P36D, P36E and P36F.

Of these six magnets the first three, CM1, CM2, and CM3 (Fig. 1), serve to control the rotary motion of a type wheel P37; the next two CM4 and CM5 (Figs. 3 and 1 respectively) serve to control the axial motion of this same type wheel; while the sixth magnet PM (Fig. 2) is the printing magnet which effects the actual printing and also advances the paper tape and inked ribbon. As illustrated in Figs. 1 and 2, the six magnets are arranged in two tiers of three each, the arma-

tures of the magnets in the lower tier being arranged beneath the same and the armatures of the magnet of the upper tier being above the same.

The type wheel P37 is mounted on a square shaft P38, the end portions of which however are circular and are rotatively supported in bearings P39 and P40 fixed to arms P41, P42 of bracket P43. The front end of shaft P38 extends through bearing P39 and carries a pinion P44 which meshes with the teeth of a rack P45 slidably supported in projections P46, P47 of arm P41. The bracket P43 thus forms the frame-work of a self-contained unit comprising the type wheel P37, shaft P38, pinion P44 and rack P45. This bracket P43 is supported from plate P35.

Type wheel P37 is provided with a plurality of rows of characters, the form illustrated being provided with three rows; and when none of the selecting magnets is energized the wheel is located with a character approximately at the center of the central row in printing position. Mechanism is provided for selecting other characters by rotating the type wheel in either direction, and by shifting the wheel axially, as already indicated.

For rotating the type wheel P37 in either direction from its normal or home position, the rack P45 must be pulled up or down. The motion of this rack is controlled on the one hand by a spring P48 constantly tending to pull it upward, and on the other hand by an aggregate motion linkage which sometimes pulls it down below its normal position and sometimes lets it rise above its normal position.

As indicated generally in Fig. 6 and as also clearly shown in Fig. 1, the aggregate motion linkage comprises an initial flexible band P52, a first lever P49, whose right end is connected to such initial band, a second band P53 connected to the left end of such first lever P49, a second lever P50 whose left end is connected to such second band P53, a third band P54 connected to the right end of this second lever P50, a third lever P51 whose right end is connected to this third band P54, and finally a fourth band P55 connecting the left end of lever P51 to the rack P45 which is to be moved.

The inputs of motion from magnets CM1, CM2, CM3 to this aggregate motion linkage are applied over three bars P56, P59 and P62. The first bar P56 is connected to the initial flexible strap P52 at the right hand end of lever P49 (Figs. 1 and 6). The second bar P59 carries the central fulcrum of lever P50. The third bar P62 carries the central fulcrums of both the levers P49 and P51. The end fulcrums of the levers, that is, the regions at which the flexible bands apply their forces, are provided with convex arcuate surfaces, which extend over a sufficient arc so that the flexible bands lie against these arcuate surfaces even in the most tilted positions of the levers. The arcuate surfaces of each lever center about the central fulcrum of the lever. The direction in which the belts extend is parallel to the direction of movement of bars P59 and P62 which carry the central fulcrums of the levers P49, P50 and P51.

Sliding bar P56 is normally pulled down against back stop P57 by the tension in strap P52 and spring P57' of the linkage, but is raised by arm P58 or armature P36A whenever magnet CM1 is energised. In like manner sliding bar P59 is normally pulled down against back stop P60, but is

raised by arm P61 of armature P36B upon energisation of magnet CM2.

It will be noted that both bars P56 and P59 are arranged so that upon the energisation of the corresponding magnets CM1 and CM2 these bars move against the pull which is constantly maintained in the aggregate motion linkage by spring P48. Upon de-energization of such magnets CM1 and CM2 the bars P56 and P59 are correspondingly returned against their back stops P57 and P60 by the tension of the linkage.

In accordance with a feature of the present invention however the motion of the bar P62 upon the energization of its corresponding magnet CM3 is arranged to be in such direction as to correspond to a yielding to the tension in the linkage; for if all three bars were arranged to move against the pull of the linkage, every combination of energization of magnets CM1, CM2 and/or CM3 would always give a downward motion of rack P45 from its home position. But for maximum speed it is desirable that rack P45 should move sometimes up and sometimes down from its normal or home position, thus reducing the maximum distance it must move. For this reason bar P62 is arranged to move upward upon energization of magnet CM3, thus yielding to the tension in the linkage. The contrast between the pulling movement of bars P56 and P59 and the yielding movement of bar P62 is best seen from Fig. 6.

In accordance with a further feature of the present invention, means is provided for positively locking bar P62 against upward movement in the non-energized condition of magnet CM3, while yet permitting it to move upward upon energization of this magnet. Such means is constituted by the roller P63' mounted on one end of bar P62 and the cam P63 mounted on a horizontal slideable bar P64. In the normal non-energized condition of magnet CM3 the bar P64 is held against back stop P65 by spring P66 in such position that cam P63 prevents upward motion of roller P63' and bar P62. Thus in the normal position a vertical force on bar P62 cannot slide bar P64 horizontally no matter how great the force exerted upon bar P62, for example by jerks or dynamic increases of tension in the linkage.

For sliding the bar P64 to the left a bell crank lever P67 is provided which is engaged by arm P68 of armature P36C so as to be rocked counter-clockwise upon energization of magnet CM3. Such counter-clockwise motion of P67 pulls bar P64 to the left by means of flexible strap P69, allowing roller P63' to roll up the sloping cam face, thus elevating bar P62. Upon the release of magnet CM3 the bar P64 is retracted to the right by spring P66, thus pushing down bar P62 and bringing cam P63 and roller P63' into the position shown in the drawing.

Whenever the cam P63 and roller P63' are in the position shown in Figs. 1 and 6, the bar P62 is positively held against a vertical movement and thus no oscillation of this system between the opposing tensions of springs P66 and P48 can occur. If it were not for the action of the locking means P63 and P63', which effectively prevents transmission of forces from bar P62 to bar P64, every movement of the aggregate motion linkage would give rise to an oscillation or pendulum action, determined by the masses of the linkage and the stiffnesses of the two opposing springs P66 and P48.

The central fulcrums of the selecting levers P49, P50 and P51 are appropriately spaced between the end fulcrums of these levers so that

the aggregate motion resulting from selective movement of these levers by various combinations of bars P56, P59 and P62 will shift rack P45 either upwardly or downwardly from normal position by successive steps which correspond to the spacing between the characters on type wheel P37. With levers proportioned and arranged as indicated in the drawings, the type wheel may be located in any one of two circumferential positions above and three below the character that is in printing position when the type wheel is at rest, by selectively energizing magnets CM1, CM2 and CM3.

An arrangement may be provided for throwing out any of the armatures of these magnets, similar to that described hereinafter in connection with magnets CM4 and CM5. This is illustrated in Fig. 7 in connection with armature P36C of magnet CM3. Arm P68 is seated in a notch P67a at an end of lever P67 and is removable therefrom by endwise movement of the arm and armature, which are then tilted backwardly by spring P67b. Figures 7 and 8 likewise disclose the use of springs P15b and P16b for tilting armatures P36D and P36E outwardly when arms P15 and P16 are released from their respective notches.

In addition to the aggregate motion mechanism above described for controlling the rotary motion of the type wheel in response to energization of magnets CM1, CM2 and CM3, further means is also provided for shifting this type wheel axially one step to the left or right from normal or home position. Such axial shifting means comprise a three-armed bell crank lever P70, P71, P81 whose arm P71 carries a pin P74 engaging an annular groove in the forward end of the type wheel P37 and whose arm P70 is in turn actuated by a pin P72 on the rear end of a rocking lever P73. The rocking lever P73 is engaged at one end by arm P15 of armature P36D, and at the other end by arm P16 of armature P36E.

The attraction of armature P36D by magnet CM4 will rock lever P73 clockwise, turning bell crank P70 counter-clockwise and shifting type wheel P37 forward. Attraction of armature P36E by magnet CM5 on the other hand will rock lever P73 counter-clockwise, turning bell crank P70 clockwise, and shifting type wheel P37 toward the rear of the machine.

For returning bell crank P70 to its intermediate position when neither magnet CM4 nor CM5 is energized, a pair of arms P77 and P78 having parallel laterally extending jaws P78' (Fig. 3) are provided which are drawn together by spring P79 and which embrace between them a block P80, attached to the main plate P35, and also the lower arm P81 of bell crank P70—P71—P81.

Thus, any displacement of this bell crank, either toward the rear or the front of the machine (i. e. either to the left or right from its normal position, as viewed in Fig. 1) forces the two arms P77 and P78 apart against the action of the spring P79. The tension of this spring, therefore, tends at all times to restore the bell crank P70—P71—P81 to its normal intermediate position, whereby the type wheel P37 is brought to the intermediate, normal or home axial position shown in Fig. 1.

When the printer is used with certain types of actuating apparatus it is sometimes desirable to prevent magnet CM4 or CM5 from affecting the printing. This is conveniently accomplished by locating the ends of arms P15 and P16 in lateral notches P15a and P16a in the ends of lever P73, said arms and their respective armatures being movable laterally so that the arms can be shifted

out of said notches, allowing the armatures to swing away from the magnets into inoperative position.

In addition to the mechanism above described, 5 which all serves for positioning type wheel P37 rotatively and axially under the control of magnets CM1, CM2, CM3, CM4 and CM5, certain other equipment is provided for supporting and feeding the paper tape and inked ribbon and for 10 printing the selected characters, such equipment being controlled by printing magnet PM. Fixed to the left side of armature P36F is an arm P82, best shown in Fig. 2, carrying a pin P83 which engages in an elongated slot in actuating arm P84 of printing lever P85. This printing lever is pivoted at P86 and held out of contact with the type wheel by spring P87. Thus, upon energization of magnet PM armature P36F swings down about its pivot P88, so that pin P83 is moved to the left. This movement of pin P83 swings actuating arm P84 clockwise about its pivot P86 and thus the printing lever P85, which is integral with arm P84, is swung downward toward the type wheel. Just before this lever P85 strikes the type wheel the armature P36F abuts against the core of magnet PM. Due to the momentum of printing lever P85 the latter swings on downward until the rubber hammer P89, which is clamped into the end thereof, forces ink ribbon P90 and paper tape P91 against the type wheel P37 to effect the printing 20 of the selected character.

Arm P82 also is provided with a slot P92 into which extends pin P93 of rocker arm P94. This rocker arm is pivoted at P95 and its lower end lies 25 in line with the end of slideable lever P96. Thus when arm P82 swings toward the left side of the machine (i. e. to the left in Fig. 2) upon the energization of printing magnet PM, the rocker arm P94 is thereby swung counter-clockwise round its pivot P95 and the lower end thereof pushes sliding bar P96 to the right, as viewed in Fig. 2, against the tension of spring P97. Such movement of bar P96 to the right carries with it a lug P98 engaging a pin P99 carried by arm P100 30 of centering lever P101. This centering lever P101 is thus swung counter-clockwise by spring P102 so as to engage centering cam P103 for the purpose of bringing the type wheel exactly to the centre of that rotary position in which it approximately stands.

Such motion of bar P96 also retracts pawl P104 mounted on the bar, so that the pawl engages the next tooth of the ratchet wheel P105. Upon the de-energization of printing magnet PM and the consequent retraction of bar P96 to the left under the influence of spring P97, this pawl P104 rotates ratchet wheel P105 clockwise one step, thus turning the knurled paper advancing wheel P106 to which wheel P105 is fixed, so as to move the paper P91 one step forward. A holding pawl P107 prevents the ratchet wheel P105 from rotating backwards during the withdrawing movement of stepping pawl P104.

A rubber roller P108 is carried by arm P109 which is pivoted at P110 and urged clockwise by spring P111, so as to press the rubber roller P108 against the paper P91. A paper guiding roller P112 is mounted on the same pivot P110 which carries arm P109. Still further rollers P113, P114 70 guide the paper tape P91 from a supply roll P115 at the right side of the machine to a suitable point from which this tape can feed toward the left of the machine under roller P112, between knurled wheel P106 and rubber roller P108, and hence out over type wheel P37.

The printing magnet PM also effects the advancement of the ink ribbon. At the left side of armature P36F (i. e. the right side as seen in Fig. 1) is fixed an arm P154 which upon energization of magnet PM presses against the top end of a vertically slidable bar P155 of the ribbon advance assembly shown in Figs. 4 and 5, thus forcing this bar downward against the reaction of a spring P156. A pin P157 in bar P155 engages the slotted end of a rocker arm P158, causing the latter to rock counter-clockwise about its pivot P159. The other end of rocker arm P158 carries a double stepping pawl P190, which is capable of engaging with either ratchet wheel P191 associated with the front ribbon spool P192 or ratchet wheel P193 associated with the rear ribbon spool P194.

When in the position illustrated in Fig. 4, the double pawl P190 is pressed against ratchet wheel P191 by toggle spring P195 which pulls upward on pin P196 of double pawl P190 at such an angle as to urge the pawl to engage the teeth of wheel P191. If the double pawl P190 is swung against ratchet wheel P193, due to the toggle action, spring P195 will press the pawl against such left hand ratchet wheel.

With the pawl in the position shown the counter-clockwise rocking arm P158 retracts this pawl so that the latter falls behind the next tooth of ratchet wheel P191 under the pressure of spring P195. Subsequently, upon the de-energization of magnet PM and upon the consequent upward movement of bar P155 under the force of spring P156, rocker arm P158 swings back clockwise, causing the pawl P190 to advance ratchet wheel P191 by one step.

A double holding pawl P197, Fig. 5, is disposed generally behind stepping pawl P190, being pivotally supported from fixed base plate P198 rather than from rocker arm 158. A toggle spring P199 pulls upward on a pin P200 extending through a slot in plate P198 and fixed to holding pawl P197.

The holding pawl P197 is also provided with a forked portion P201 which straddles pin P196. Fork P201 is sufficiently loose on pin P196 so that the holding pawl and stepping pawl can rise and fall independently of one another for clearing the peaks of the teeth and dropping into the depressions between the teeth of the ratchet wheel P191. The engagement of fork P201 with pin P196, however, ensures that when stepping pawl P190 is swung over to the ratchet wheel P193, the holding pawl P197 will likewise swing over to this ratchet wheel.

The change-over from the one ratchet wheel to the other ratchet wheel, or vice-versa, for the purpose of reversing the direction of advance of the ribbon is effected under the control of a rocker member P202 pivotally supported on base plate P198 by pivot P203. In accordance with a feature of the present invention, rocker member P202 carries at its ends two plates P204, P205 loosely pivoted on P202 but restrained by pins P206, P207 and slots P208, P209 so as to have only a limited angle of freedom. Plate P204 carries at its upper end a pair of pins P210, P211 while plate P205 carries a similar pair of pins P212, P213. Ink ribbon P90 extends from each of the reels P192 and P193 directly to the nearest pair of pins, and is of the conventional type which is provided near each of its ends with a rivet or stud (not shown) to actuate ribbon reversing mechanism. The space between each pair of pins, such as P209—P210, is so narrow that

it will not permit the passage of such rivet or stud. The freedom of movement of each of the plates P204, P205 is sufficiently great so that each such plate can accommodate itself to the changing path of the ribbon as the reels vary from full to empty; thus it is unnecessary to pass the ribbon over a fixed pulley between the reel P192 and the pins P210, P211.

When the ribbon P90 becomes almost completely unwound from the left hand reel, for example, the corresponding stud on the ribbon will engage pins P210, P211 and upon continued advance of the ribbon will finally tip rocker member P202 clockwise into reversed position, the rocker member being held yieldably in either position by the engagement of spring nose P202a with suitable notches in the rocker member. Point P224 is thus shifted into position to engage shoulder P225 on the pawl P190 when the latter is next shifted upwardly, swinging both pawls into engagement with ratchet wheel P193. The pawls are similarly shifted back into engagement with ratchet wheel P191 when a ribbon stud is caught by pins P212, P213, rocking the member P202 counter-clockwise and shifting point P222 into position for engagement by shoulder P223.

Provision is made also for the use of a two color typewriter ribbon with the printer described herein. A ribbon shift mechanism comprising a plate P230 supported so as to swing from a stud P231 fixed to plate P34, and carrying four rollers P232, P233, P234 and P235 for guiding ribbon P90, is shown in Figures 1, 2 and 3. The movement of plate P230 and consequently the shifting of the ribbon is therefore shown as controlled by magnet CM3. As previously described, energization of CM3 causes the movement of slide P64 toward the rear of the machine (to the left as shown in Fig. 1). A projecting part of slide P64 engages one arm of bell crank P126 pivoted at P127 to bracket P128, and causes the opposite arm of the bell crank to engage ear P129 integral with plate P230, thereby swinging plate P230 outward from the machine. Spring P66 (Fig. 2) holds plate P230 against the bell crank when the ribbon is shifted, and against adjustable stop screw P130 when the ribbon is in unshifted position.

The ribbon shift may be dispensed with by removing the actuating bell crank P126 to eliminate shifting of plate P230, or by adjusting stop screw P130 so that the ribbon remains permanently in the shifted position, and/or by using a one color ribbon and disregarding shift operations.

There are applications where a ribbon shift actuated from a particular selecting impulse will be useful, for example when a ribbon color shift mechanism may be actuated to cause printing in red for every character which is selectable with the aid of magnet CM3, while for those characters whose selection involves no energization of the CM3 magnet the printing will be in black. Preferably the arrangement of the characters on the type wheel would then be such that the numerals 0-9 are selected without energization of magnet CM3, whereas signs denoting the various arithmetical operations are selected by impulse combinations which involve the energization of a magnet CM3. Thus the numerals 0-9 would be printed in black and the punctuation or operation-indicating marks in red. Magnet CM3 or a similar actuating means may be arranged to cause three steps of rotation of the type wheel. Then if energization of magnets CM1, CM2 and CM3, for example, simultaneously

produces the same effect as if none of these is energized, certain characters (corresponding to no rotation of the type wheel) can be selected either with or without energization of magnet CM3, making it possible to print such characters selectively in either red or black.

It will be noted that in a four impulse code arrangement no provision may be made for the usual word space operation. Since the device as disclosed is intended to record figure groups which are separated by mathematical signs, this conventional function of a printing device is not required. The respective problems may be separated otherwise, for instance by the three period groups; and on account of the novel disposition of the paths of the ribbon and tape where the tape is fed at substantially a right angle to the path of the ribbon, effective visible printing is achieved in a type wheel printer.

It will be noted that the characters indicated on the type wheel are not reversed, as is usual. Tape P91 overlies the type on the typewheel, as shown in Fig. 1, and the ribbon P90 is fed across the upper surface of the tape, so that when the print hammer strikes, the impression of the type is received from the under side of the tape. At any time the tape may be pulled manually against the friction of pressure roller P108 and roller P106 to withdraw a length of tape from the printer. Obviously, if a so-called word space is required, this can be accomplished by the operation of magnet PM after the selection of a blank space on the typewheel, assuming that a code is used in which such a selection would be available.

The embodiment shown in Figs. 7 to 11 employs mechanisms similar in many respects to the form shown in the preceding figures, and corresponding parts are identified by the same numerals. This embodiment is particularly adapted for mounting in a cabinet with the side shown in Fig. 7 uppermost; and in order to provide apparatus that is more suitably proportioned for this purpose and with the main operating parts and replaceable supplies in readily accessible position, the mechanism has been rearranged, and in particular provides a tape feed extending lengthwise of the type wheel, with the ribbon at right angles thereto.

The aggregate motion lever system for rotating the type wheel is substantially the same, and the actuating magnets are similarly mounted. The paper tape supply roll 115 is carried by a rotary one-sided spool 250 mounted on top plate 251 supported by brackets 252 from plate P35. The tape passes over suitable guide rollers 253, between feed roller 254 and pressure roller 255 and into guideway 256 extending axially along and adjacent the type wheel P37. The margins of the guideway are turned over to hold the tape in place, and a suitable gap in printing position permits the printing hammer 257 to force the ribbon and tape against the type. The tape P91 projects to the left of the guideway 256, where it can be easily read, withdrawn and torn off as desired.

The paper tape is fed by roller 254 driven by step mechanism actuated by magnet PM. The mechanism includes actuating arm 264 fixed to armature P36F and engaging the lower end of a pawl rocker arm 265 (Fig. 11) pivotally mounted on the shaft 266 of feed roller 254. The roller is hollow to accommodate the drive mechanism, and is mounted on the upper end of the latter shaft. A pawl 267 on arm 265 engages

ratchet wheel 268 on shaft 266, while a holding pawl 269 mounted on plate P35 likewise engages the wheel. The arm 265 is biased against the actuating arm 264 by leaf spring 270. With this arrangement the feed roller 254 will be rotated one step at each energizing of the magnet PM.

A somewhat different linkage is employed in this embodiment to shift the type wheel P37 in an axial direction. Actuating arms P75 and P76 engage the ends of a three armed lever 73 (Fig. 7), the center arm of which projects laterally and engages a link 273 connected to wheel shift lever 71, pivoted at its outer end on bracket 274 which is mounted on top plate P35 and carries wheel shaft P38. The lever 71 is pressed toward central position by the same construction as that employed in the previous embodiment, including the spring pressed opposed arms 77 and 78 corresponding to arms P71 and P78 and mounted on bracket 274.

A lower stub shaft 275 is journaled in bracket 260 and carries printing hammer 257 freely mounted thereon and held by spring 87 against the hammer propelling arm 276 fixed to shaft 275. The end of shaft 275 is connected by rocker arm 277 (Figs. 8 and 10) to rocking plate 262 through a pin and slot connection 278, arranged so that the inward movement of armature P36F when magnet PM is energized will rock shaft 275, throwing the hammer 257 inwardly against the ribbon and tape, and against an adjustable stop 279 carried by bracket 260.

Plate 262 is carried by pivot shaft 261 on bracket 260 and is biased counter-clockwise by spring 263. The centering lever P101 is freely mounted on shaft 261 and carries a depending arm 271 (Fig. 8) yieldably held by spring 272 against pin 285 on arm 286 fixed to shaft 275. With this arrangement the actuation of armature P36F and the rotation of shaft 275 will swing lever P101 upwardly into engagement with centering cam P103; but in case of interference the spring 272 will permit lever P101 to yield without damaging the actuating mechanism.

The ribbon feed mechanism is essentially the same as that employed in the former embodiment, but is mounted across the left end of the frame as seen in Figs. 7 and 8, being shown best in Fig. 9. In this arrangement the rocker arm P158 is actuated through a link 280 rearwardly biased by spring 281 and pivoted to arm 282 on shaft 275. The ribbon P90 is guided over rollers 283 on rocking plate 230 pivoted by studs 231 on ribbon mounting plate 198 attached to base plate P31. A spring 284 presses the plate 230 inwardly against a projection on ribbon shift arm 126 (Fig. 7), which is pivoted at one end to bracket 274 and has a lateral extension 288 engaging an arm of bell crank P67. This construction provides a run of inked ribbon P90 extending across the outer face of the tape P91 in line with hammer 257 (Fig. 9).

The described embodiments are arranged to provide compact units taking up a minimum of space and adapted for housing in metal cabinets, with the printed tape fed out of the cabinet in position for convenient reading. The embodiment disclosed in Figs. 1-6 is suitable for mounting in vertical position as shown, while the remaining embodiment is adapted for mounting in flat position, and may be combined with suitable keyboard mechanism to form a self-contained unit suitable for desk use.

While two embodiments have been described and illustrated, the disclosure is not intended to

limit the invention, since various other modifications may be made within the scope of the invention as set forth in the claims.

What is claimed is:

1. A code-controlled printer comprising a printing device and means for selecting a character on said device, including a plurality of levers, means linking the levers together to form an aggregate motion linkage, a plurality of selectively-operable magnets, and a plurality of lever-devices operated by corresponding ones of said magnets and including links reciprocable side by side and each providing at least one intermediate fulcrum of said levers.

2. A code-controlled printer comprising a printing device and means for selecting a character on said device, including a plurality of levers at least one of which consists of an intermediate fulcrum portion and two arms of unequal length at opposite sides of said intermediate fulcrum portion, means linking the levers together to form an aggregate motion linkage, including flexible members connecting end fulcrums of the levers, means for maintaining the flexible members under tension, a plurality of selectively operable magnets, and a plurality of lever actuating devices each engaging a lever fulcrum, said lever-actuating devices being selectively responsive to the operation of said magnets to displace said latter fulcrums, said end fulcrums comprising for each lever arcuate faces concentric with the intermediate fulcrum and bearing against the inner faces of the flexible members connected to said lever.

3. A code-controlled printer comprising a printing device and means for selecting a character on said device, including at least three levers, means linking the levers together to form an aggregate motion linkage, including connections between the ends of successive levers, a plurality of selectively operable magnets and a plurality of lever actuating devices each responsive to the operation of one of said magnets, one device engaging intermediate fulcrums of two of said levers and another device engaging the intermediate fulcrum of a third lever.

4. A code-controlled printer comprising a printing device, means for feeding an inked ribbon through a printing station, character-selecting means including a plurality of selecting magnets and an aggregate linkage connected to said printing device to shift the same and operated by one or any number of said selecting magnets, and means operated by one of said magnets for shifting the ribbon laterally at the printing station.

5. A code-controlled printer comprising a printing device and means for selecting a character on said device, including a plurality of levers, means linking the levers together to form an aggregate motion linkage, a plurality of selectively-operable magnets, and a plurality of lever-actuating devices each responsive to the operation of one of said magnets for displacing a fulcrum of a lever, one of said lever-actuating devices being directly connected to and displacing one fulcrum of a lever and another of said lever-actuating devices being directly connected to and displacing fulcrums of two levers.

6. A code controlled printer comprising a printing device and means for selecting a character on said device, including a plurality of levers, means linking the levers together to form an aggregate motion linkage and including a flexible member

connecting end fulcrums of two levers and means for maintaining the flexible member under tension, a plurality of selectively operable magnets, and a plurality of lever-actuating devices each responsive to the operation of one of said magnets for displacing a fulcrum of a lever.

7. A code-controlled printer comprising a printing device and means for selecting a character on said device including at least two links longitudinally movable in substantially parallel adjacent paths, at least three levers with the intermediate fulcrums of two of said levers connected to one of said links and the intermediate fulcrum of the other of said levers being connected to the second link, a connection between one end of the two levers fulcrumed on the first link to the corresponding end of the lever fulcrumed on the second link, a connection between the second end of the first lever and the corresponding end of the third lever, a connection between the second end of the third lever and the printing device, a plurality of selectively operable magnets, and devices operable in response to the operation of said magnets for operating the free end of the first lever and the longitudinally movable links.

8. A printer as set forth in claim 7 in which the connections between lever ends are flexible bands and the lever ends are circular-arc ends of radii equal in length to the corresponding lever arms and on which the flexible bands wrap and unwrap.

9. A printer as set forth in claim 7 in which the first lever is located between the other two.

10. A printer as set forth in claim 2 in which at least two of the levers have arms of different lengths.

11. A code-controlled printer comprising a printing device and means for selecting a character on said device including a plurality of levers, means linking the levers together to form an aggregate motion linkage, a series of selectively actuated magnets, means operated by the magnets for differentially actuating said linkage including links movable in parallel side-by-side paths and each engaging a lever fulcrum and operated by means including one of said magnets, and means including a magnet-controlled cam for shifting one of said links and the fulcrum engaged thereby.

12. The combination according to claim 7 wherein each of said links is spring-urged to a normal position when said magnets are deenergized.

LADISLAS KOZMA.
GEORGES XAVIER LENS.
